MUSICAL DRUM AND THE LIKE PERCUSSION INSTRUMENT

Charles Frederick Deans and Albert Edmund Busby, Beverley, England

Application February 5, 1938, Serial No. 189,002
In England December 17, 1937

2 Claims. (Cl. 84—419)

The present invention relates to musical drums particularly those known as side drums and kettle drums intended for orchestral purposes.

Drums of the kind mentioned are generally supported upon a tripod or other stand which, at its upper end, has a number of arms to receive the drum and, at its lower end, has struts to support legs extending from the central stalk or stem, the several arms, legs and struts being foldable or otherwise collapsible for the purpose of ease of transport. The arms are also extensible and adjustable in regard to their angle with the axis of the stalk, whereby they will hold drums of varying diameters and at any desired inclination, whilst the struts and legs are also slidable upon the stem or afford adjustment of the height at which the drum is supported. The drums consist of a hollow cylindrical shell the ends of which are closed by skins stretched around the peripheries of the shell by screw or the like means, these skins being known as "heads." A series of "wires" or "snares" is disposed diametrically across the outer face of the lower or snare head of the drum, whilst, in some types of drums, similar wires are also disposed diametrically of the inner or underneath face of the upper or batter head. Each set of snares is held taut by a tensioning device and may be displaced axially of the drum in order to cause the snares to bear upon the face of the snare or batter head as the case may be, or to be moved away therefrom to vary the tone of the drum. It will be thus seen that with a drum provided with both internal and external wires or snares a limited number of tones are available.

Other devices such as a pad adapted to be brought into a position to bear on the under face of the upper or batter head are sometimes provided to render the drum less resonant, such devices being operated by means similar to those for displacing the wires or snares.

Axial displacement of the pad or the wires has been effected hitherto by levers situated on the cylindrical walls of the casing at positions readily accessible to the hand or drum-stick of the player, the levers being connected to bearers for the displacing or tensioning devices through the medium of links lying internally of the casing. With a construction of this kind, the drummer must necessarily interrupt his playing of the drum and in order to operate the levers and thus to "tune" the drum to one of the limited number of tones available.

The object of the present invention is to pro-

vide means which will enable the drummer to operate the wires or snares without interruption in playing of the drum, a further object being to enable an infinite variety of tones of the drum to be obtained while the drum is being played.

According to the present invention, and from one aspect thereof, the wires or snares, pads or other attachment for varying the tone of a musical drum are displaceable by a remote control consisting of a pedal operable device, whereby the hands of the operator are free for playing purposes.

From another aspect, the present invention resides in the provision of means, the employment of which enables the wires or snares, pads, or other attachment for varying the tone of a musical drum, to be displaced to an infinitely variable degree, within predetermined limits, to vary the pressure with which the wires or snares, or other attachment, bear upon the head of the drum to so permit of a variety of tones being obtained.

Preferably the pedal means are connected with the wires or snares or other device through the medium of a Bowden cable mechanism, although other means such as rods and levers or pneumatic or hydraulic or electrically operated means, as may be found suitable for the purpose, may be employed.

If desired, means may be provided, either in the remote control or in the mechanism housed within the shell of the drum, for the purpose of retaining the wires or snares or other device in the position to which they have been displaced by the pedal.

The remote control in accordance with this invention may consist of a pedal forming a part of the stand or support for the drum or an attachment thereto, or may comprise a pedal formed as a unit separate from the support.

In order that the invention may be readily understood reference is made to the accompanying drawings, in which:

Figure 1 is a perspective view of a drum supported upon a stand and provided with a remote control in accordance with this invention, the skins or heads of the drum being removed for the sake of clarity.

Figure 2 is a section through the casing of the drum on a line normal to wires or snares running diametrically of the snare head, and of a chordal length much smaller than the diameter of the drum.

Figure 3 is a side view of Figure 2.

55

Figure 4 is a sectional view of part of a drum casing showing the snares for the upper or "batter" head and the means for displacing the same.

Figure 5 is a similar perspective view to Figure 4, but shows a device comprising a pad for modifying the tone of the drum by bearing upon the upper or batter head, and the means for operating the same in accordance with this invention.

10 Figure 6 is a longitudinal sectional view of a remote control device, in accordance with this invention, formed as a separate unit.

Figure 7 is a perspective view of a drum, with the skins or heads removed to show more clearly 15 means for enabling the wires or snares to be maintained in the position to which they have been displaced by the remote control.

Referring to Figure 1 of the drawings, a drum having a shell or casing 11 is supported upon a 20 stand having a central stem 12. The stem 12 has a plurality of arms extending radially from the upper end thereof each of which arms has an upturned end 13 to embrace the casing 11, whilst at its lower end the said stem 12 is provided with 25 struts 14 for the legs 15, the struts 14 and the legs 15 being adjustably connected to the stem 12 whereby the height of the drum may be varied and the stand rendered collapsible.

The drum is provided with a series of wires or 30 snares 16, the several wires of which have anchorage in a housing 17 which may also embody one or more devices for tensioning the wires either collectively or separately.

As will be seen from Figures 2 and 3, the housing 17 for each end of the wires or snares is supported upon a diametrical bearer strip 18, which emerges from the casing 11 through slots 19 of a depth to permit of displacement of the strip 18 to enable the wires or snares 16 to be moved away from the lower or snare head 20.

40 Disposed above the strip 18 and arranged parallel therewith is a rod or spindle 21 which is trunnioned at diametrically opposed points on the casing 11 in bearings 22. The rod or spindle 21 has rigidly secured thereto a lever 23 which has its upper extremity connected at 26 to a sectoral member 24 pivotally connected at its apex to a bracket 25 mounted on the strip 18. It will be seen that upon rotation of the shaft 21 the lever 23 is angularly displaced about the centre of said shaft 21, such displacement causing an angular displacement of the sectoral member 24 about its apex. Movement of the sectoral member 24 however, is under the influence of the path of the pin 26 which moves in an arc about the rod or spindle 21, thus causing movement of the strip 18 in a direction away from the rod 21, such movement, of course, being transmitted to the wires or snares 16 which are displaced by a corresponding amount.

60 A shackle 27 connected to the pin 26 is adapted to receive the end of the inner cable 28 of a Bowden cable mechanism, said inner cable 28 entering the casing 11 through a hole which, for preference, is formed in an enlargement 29 on the cylindrical casing 11, the primary function of which enlargement is to house the tensioning screws 31 for the rims 33, 35 of the drum. By 65 virtue of the sides of the enlargement 29 being substantially radial of the casing 11, such sides are substantially normal to the cable 28 and the enlargement thus forms a convenient stop for the outer casing 30 of the Bowden cable mechanism. It is desirable that the enlargement 29 70 should be provided with a screwed hole to re-

ceive a tensioning device 32 (Fig. 4) for adjustment of the outer casing 30.

As will be seen from Figure 1 of the drawings, the stem 12 of the stand or support has loosely mounted thereon a bracket 36 forming the fulcrum of a pedal operated lever 37, said lever 37 having connected thereto the end of the inner cable 28, remote from the shackle 27. The outer casing 30 of the Bowden cable mechanism is stopped at the end remote from the enlargement 29 by an arm 39 of a bracket 38 mounted upon the stem 12 at a suitable distance above the bracket 36. The brackets 36, 38 are relatively adjustable upon and removable from the stem 12, by means of thumb-screws, whilst the lever 37 15 and the arm 39 are foldable relatively to their respective brackets to facilitate the stand or support being folded into relatively small compass. The height of the pedal 37 is thus adjustable to suit the foot of the player whilst the tension on 20 the outer casing 30 may be adjusted by movement of the bracket 38.

Furthermore, the cable 28 may be easily removed from the lever 37 and the arm 39 by sliding the said cable 28 out of its engagement with 25 in the lever and arm by means of slots, so permitting of the easy dismantling or assembly of the drum and its stand.

It will be appreciated that pressure applied to the pedal 37 causes the angular displacement of 30 the rod or spindle 21 to cause movement of the wires or snares 16 axially of the casing 11 in a direction away from the lower or snare head 20. Such axial movement of the wires or snares 16 is against the action of a spring 34, one end of 35 which is secured to the pin 26 and the other end of which is secured to a convenient point on the walls of the casing 11, the spring 34 causing the wires or snares to resume their normal position upon the lower or snare head 20 when pressure 40 upon the pedal 37 is released.

Referring to Figure 4 of the drawings, which illustrates the application of the present invention to the wires or snares which normally bear upon the under face of the upper or batter head 45 of the drum, each end of the wires 16 are anchored in a member 40 slidably in a chassis 41 mounted on the inner walls of the casing 11. The slide 40 has pivotally connected thereto a bracket 42, the upper end of which has a pivotal 50 connection 26 with the lever 23 which is angularly displaceable in unison with the rod or spindle 21 carried in trunnions at diametrically opposed points on the casing 11.

The pin, comprising the pivotal connection 26, 55 also forms the connection with the shackle 27 of the inner cable 28 of the Bowden cable mechanism the outer casing of which is stopped by the enlargement 29 as described with reference to Figures 1 to 3.

Angular displacement of the rod or spindle 21, therefore, causes displacement of the slide 40 relatively of its chassis 41 to displace the wires or snares 16 axially of the casing 11 in a direction away from contact with the batter head 50. A 65 similar displacement is imparted to a slide in a chassis member at the opposite end of the rod 21. Such movement, of course, is caused by depression of a pedal such as that described with reference to Figures 1 to 3 inclusive, and is 70 against the action of the spring 34 which causes axial movement of the wires or snares 16 in the opposite direction, i. e. to resume their normal position in contact with the upper or batter head 50, when pressure upon the pedal is released. 75

The slide 40 and bracket 42 (as is the sectorial member shown in Figures 1 to 3) are provided with recesses or holes of suitable shape and size to prevent movement being hindered by the rod or spindle 21.

Figure 5 illustrates the application of the present invention to the operation of a pad 44 for modifying the resonance of the upper or batter head of the drum. A normal position for such a pad, of course, is away from contact with the under face of the upper or batter head, as shown in Figure 5. The pad 44 is mounted upon the upper end of a member 43 slidable in its chassis 41. Movement of the slide 43 in a direction parallel with the axis of the casing 11, to cause the pad 44 to bear upon the under face of the upper or batter head 50, is effected by the angular displacement of a sleeve 45 mounted on a stud trunnioned on the inner walls of the casing 11. The sleeve 45 carries a radial arm 46 which is cranked or bent to engage within an arcuate slot 47 formed in the slide 43. Angular displacement of the sleeve 45 is effected by means of the inner cable 28 the end of which is provided with a shackle 27 engaging a bifurcated yoke mounted on the lower end of the radial arm 46. Thus, pressure applied to a pedal to which the remote end of the cable 28 is connected causes the pad to be moved upwardly in a direction parallel with the axis of the drum to bear against the upper or batter head 50. Such movement of the pad is against the action of the spring 34 which causes the pad to resume its normal position when pressure on the pedal is released.

It will be appreciated that the present invention may be embodied in any device or attachment for modifying or effecting alteration in the tone of a drum other than those hereinbefore described with reference to the accompanying drawings which show the application of the invention to the operation of the wires or snares or pad with which drums of the kind mentioned are usually provided. A single pedal may operate more than a single set of wires or snares or other attachment or a pedal may be adapted to operate each set of wires or snares and other device. In such an event, the pedals would be situated in close proximity to one another and may have their fulcrums in a common bracket such as 36 and have the outer casings of their attached Bowden cables stopped in arms of a common bracket such as 38. Again, a single pedal may be adapted to operate more than one set of snares or other device.

The pedal may be mounted on any convenient part of the stand or support for the drum or be mounted upon a convenient part of a so-called "Console" for reception of more than a single drum and other equipment to be played by the drummer.

In the construction according to Figure 6, the pedal is mounted remote from the stand or support for the drum. A housing 51 for the pedal 37 comprises a substantially rectangular box or casing adapted to be placed on the floor in a position readily accessible to the foot of the player. The pedal 37 is fulcrumed upon a rod or spindle arranged transversely of the casing 51 and is disposed longitudinally thereof in a substantially horizontal plane to project outside the casing and be provided with a pressure plate 52 to receive the foot of the drummer. The lever is one of the second order and accordingly is provided with a hole or recess to receive the nipple 53 of the end of the inner cable 28 of the Bowden cable, the

outer casing 30 of the cable being stopped in a recessed hole 54, which is in communication with a hole, of a diameter to permit passage of the nipple 53, by a slot. The nipple 53 may be readily removed from the lever 37 and be withdrawn from the casing 54 to permit of the easy dismantling of the apparatus. A pair of strips 55 provide a reaction means of the pressure applied to the plate 52 and prevent the casing from being affected by the pressure. The strips 55 which may have their ends upturned to form a heel rest, are hinged to the casing 51 whereby they may be folded or turned back below the casing to enable the casing to be folded into small compass. A pair of spurs or projections may be provided, one at each side of the casing, to obviate the risk of the casing working along the floor, said spurs 56 being pivotally mounted on the casing 51 whereby they may be folded inwardly thereof.

It will be understood from the drawings the snares or wires 16 are normally held in contact with the drum head by the action of the spring 34 and that the degree of movement of such wires is under the control of the pedal. The pressure upon the pedal, therefore, controls the pressure of the wires or snares upon the respective heads, and it will be appreciated that the resonance of the heads, and consequently the tone of the drum, may be varied between the limits constituted by the normal position of the snares or wires and the position of such wires when they are totally removed from the head. Again, when not in use, the position of the pad 44 or the snare wires is as shown in Figure 5, that is to say, the pad need not normally bear upon the head 50, but the pressure with which it may be brought to bear upon the head 50 may be governed by the pedal controlling the wire 28.

If desired, however, the present improvements may be applied to cause movement of the wires or snares, or a pad or other attachment, from an abnormal position to a normal position.

Again, where the housing 17 embodies a tensioning device for the wires 16, the mechanism in accordance with the present invention may be applied to vary the tension of the wires, as for example, through the medium of a bell-crank lever, or the wires may be mounted in such housing in inclined relationship whereby the tone of the drum is rendered progressive as the wires are moved axially of the casing either internally or externally.

A flexible connection between the wires or snares other than the Bowden cable mechanism described, may be used for controlling the movement of such wires or snares as, for example, an hydraulic, or pneumatic tube may constitute the means for transmitting the movement of the pedal to the wires or snares, or this may be effected by electrically operated means. Again, if desired, the pedal may be adapted angularly to displace the rod or spindle 21 by means of a link, for which purpose the said rod or spindle 21 would be extended through the casing 11 and be connected to the link through the medium of a lever rigidly connected to the rod or spindle.

Figure 7 of the drawings shows a convenient method of retaining the wires or snares of the lower or snare head in the position to which they have been displaced by the remote control. The mechanism for causing displacement of the wires or snares 16, axially of the shell or casing 11 of the drum, is substantially the same as that described and illustrated with reference to Figure 2.

In Figure 7, however, the end of the spring 34 remote from the pin 26 is connected to a roller 57 carried by the free end of an arm 58 fulcrumed in a bearing 59 on the walls of the casing 11. The arm 58 may be angularly displaced about its fulcrumed end by means of a lever (not shown) on the exterior of the casing 11 to bring the said arm 58 to the position shown in dotted lines. The bearing 59 has stops to limit the angular movement of the arm 58 to the positions shown.

Accordingly, the spring 34 may have the function of causing the wires or snares to return to their normal position on the lower or snare head 15 or, by angular displacement of the arm 58 to the position shown in dotted lines, the spring 34 may be relieved of tension or be prevented from exerting force on the sectoral member 24. The wires or snares 16, therefore, will remain in the position 20 to which they have been angularly displaced even though pressure on the pedal, comprising the remote control, is relieved. The mechanism shown in Figure 7, of course, is utilised when it is desirable to retain the wires or snares in 25 their displaced or "off" position for a period of time during which the drummer's feet is freed from operating of the remote control.

We declare that what we claim is:

1. In a percussion musical instrument having a substantially cylindrical frame, heads carried at the ends of said frame, and snare wires for varying the tone of said instrument by variable pressure on at least one of said heads; a rotary spindle supported within said frame and extending diametrically thereof, holders between which the end of said snare wires are held in tension, means for interconnecting said holders to form a unitary structure with said snare wires, guide means, which are mounted at diametrically opposed points on the inner wall of said frame and within which the holders are slidable, for controlling the path of displacement of said snare holder unit in a direction longitudinally of said frame, conversion means connecting the snare holder unit and said rotary spindle for imparting movement to the snare holder unit longitudinally of said frame upon rotary movement

of said spindle whereby to vary the pressure of the snare wires on said head, a pedal operated control remote from said instrument, and a displaceable sheathed core cable passing through said cylindrical frame and connecting said pedal operated control and said rotary spindle for imparting rotary movement to said spindle.

2. In a percussion musical instrument having a substantially cylindrical frame, heads carried at the ends of said frame, and snare wires for varying the tone of said instrument by variable pressure on at least one of said heads; rotatable means supported within said frame and extending diametrically thereof, holders between which the ends of said snare wires are held in tension, 15 means for interconnecting said holders to form a unitary structure with said snare wires, guide means, which are mounted at diametrically opposed points on the inner wall of said frame and within which the holders are slidable, for controlling the path of displacement of said snare holder unit in a direction longitudinally of said frame, conversion means connecting the snare holder unit and said rotatable means for imparting movement to the snare holder unit longitudinally of said frame upon rotary movement of said rotatable means whereby to vary the pressure of the snare wires on said head, a pedal operated control remote from said instrument, a displaceable sheathed core cable passing 30 through said cylindrical frame and connecting said pedal operated control and said rotatable means for imparting rotary movement to said rotatable means, a spring connected at one end to said rotatable means for imparting a resilient load to said snare holder unit whereby to resist movement thereof in a direction longitudinally of said frame towards the "on" position of said snare wires, and lever means pivoted to said frame and carrying the opposite end of said 40 spring and operable independently of said pedal operated control for rendering said spring inoperative when said snares are in their "off" position.

CHARLES FREDERICK DEANS.
ALBERT EDMUND BUSBY.
